No. 895,430.

PATENTED AUG. 11, 1908.

E. COLBY.
UNDERSKIRT.
APPLICATION FILED JAN. 24, 1908.

Witnessed:
Ralph Nelson.
George Teller.

Inventor:
Emma Colby
By Elephant & Young
Attorneys.

UNITED STATES PATENT OFFICE.

EMMA COLBY, OF MILWAUKEE, WISCONSIN, ASSIGNOR TO VIOLA C. HERZER, OF MILWAUKEE, WISCONSIN.

UNDERSKIRT.

No. 895,430.

Specification of Letters Patent.

Patented Aug. 11, 1908.

Application filed January 24, 1908. Serial No. 412,381.

To all whom it may concern:

Be it known that I, EMMA COLBY, a citizen of the United States, and resident of Milwaukee, in the county of Milwaukee and State of Wisconsin, have invented certain new and useful Improvements in Underskirts; and I do hereby declare that the following is a full, clear, and exact description thereof.

10 My invention has for its object to provide a simple, economical, advantageous, comfortable and sanitary substitute for the bustle of common knowledge; said invention consisting in an underskirt, such as herein set forth with reference to the accompanying drawing and pointed out in the claims of this specification.

15 The drawing represents a side elevation of an underskirt in accordance with my invention, as the same would appear wrong side out.

20 Referring by letter to the drawing, A indicates an underskirt made from outing-flannel or other suitable fabric, the waist of the skirt being abnormally full in proportion to that of the wearer. The waistband b of the skirt is made double, and the casing, thus formed, engaged by opposite drawstrings c that are fastened at their inner ends 25 to said waistband a predetermined distance from the center of the back or from a rear placket of said skirt, these ends of said strings being preferably adjacent to side seams d of the front piece of the garment.

30 35 Sewed on the inside of the skirt, and preferably within the confines of its waistband, are the upper ends of side flaps B of material similar to that aforesaid, and these flaps are shown extending in opposite directions from 40 a rear placket of said skirt for a predetermined distance. Sewed on each flap B, below the waistband of the skirt, so as to avoid undue thickness at the waist-line of the wearer, is another flap of like material,

45 the same being shorter than the one aforesaid but otherwise of approximately the same dimension. Flaps in pairs of unequal vertical dimension and extending in opposite directions from the center of the back or

50 55 from a rear placket of the skirt are preferable, and ordinarily sufficient, but a greater number of flaps of gradually decreasing vertical dimensions may be embodied in each set. For some persons, the skirt and its flaps B may answer. It is also to be understood that if the skirt be made without the placket herein shown, a single flap B, and a single flap C extending a predetermined distance in opposite directions from the center of the back of said skirt may be substituted for the two of each in the drawing.

60 The front of the skirt is shown provided with a horizontal slit e central of same through which to pass stocking-supporters attachable to a corset, and a shield piece f is 65 preferably provided back of the slit, the same being sewed at its upper end to said skirt inside the same.

65 The skirt being put on the wearer, its strings c are drawn sufficiently tight and 70 tied to one another to secure the garment in place, it being intended that the waistband of said skirt shall come under the corset of the wearer. The drawing of the aforesaid strings causes the skirt and any and all flaps 75 of same to gather at the back and over the hips of the wearer and the gathers being suitably adjusted, the garment serves the purpose of a bustle without the annoyance ordinarily experienced incidental to the use of 80 same.

85 A garment similar to what is herein specified, is more sanitary than a bustle, in that it can be washed from time to time without detriment thereto, and it has no filling liable to work through and prick the skin of the wearer. Furthermore it is not liable to become disarranged on the wearer to the detriment of the proper hanging thereon of the skirt under which it is worn, and it has been 90 determined by practice that a better effect can be had of the outer skirt than is possible when a bustle is worn.

I claim:

1. An underskirt of abnormal fullness at the waist, drawstrings fastened at their inner ends in the waistband of the garment a predetermined distance from the middle of its back, and a plurality of flaps of skirt-material of varying vertical dimensions 100 stitched one to another and the longest one of same stitched to the waist portion of said garment, whereby all are suspended from said waist portion of said garment without undue thickness at the waist-line of the 105 wearer of same, said flaps being concentric with the aforesaid garment for a predetermined distance in opposite directions from the middle of the back of same.

2. An underskirt of abnormal fullness at 110

the waist, drawstrings fastened at their inner ends in the waistband a predetermined distance from a rear placket with which the garment is provided, and flaps of skirt material in series of varying vertical dimensions 5 stitched one to another and the longest one in each series stitched to the waist portion of said garment to avoid undue thickness at the waist-line of the wearer, each series of 10 flaps being concentric with the aforesaid garment in one direction or the other from its placket.

In testimony that I claim the foregoing I have hereunto set my hand at Milwaukee, in the county of Milwaukee and State of 15 Wisconsin in the presence of two witnesses.

EMMA COLBY.

Witnesses:

N. E. OLIPHANT,
GEORGE FELBER.

It is hereby certified that Letters Patent No. 895,430, granted August 11, 1908, upon the application of Emma Colby, of Milwaukee, Wisconsin, for an improvement in "Underskirts," were erroneously issued to "Viola C. Herzer," as owner of the entire interest in said invention; whereas said Letters Patent should have been issued to the inventor Emma Colby and Viola C. Herzer, jointly, said Viola C. Herzer being the assignee of one-half interest only in said patent, as shown by the record of assignments in this office; and that the said Letters Patent should be read with this correction therein that the same may conform to the record of the case in the Patent Office.

Signed and sealed this 8th day of September, A. D., 1908.

[SEAL.]

C. C. BILLINGS.

Acting Commissioner of Patents.